UNITED STATES PATENT OFFICE.

FRANK BORSODY, OF EAST CHICAGO, INDIANA.

COMPOUND LOCK.

Application filed September 4, 1926. Serial No. 133,546.

This invention relates to a compound lock and has for its object to provide a device of this character in which a main bolt is secured in its operative position by a primary mechanism and is further locked by a supplemental bolt operated by elements acting in conjunction with the parts first mentioned.

A further object is the provision of a key of novel construction, also compound in structure and adapted to operate the primary and the supplemental elements of the lock in conjunction with each other.

These and other objects and features of the device will be fully described in the following specification and illustrated in the accompanying drawings, in which:

Fig. 1 is a face view of the lock fully assembled.

Fig. 2 is a reverse view of Figure 1.

Fig. 3 is a view of the lock with the face plate removed and the bolt thrown, but not locked.

Fig. 4 is a section on the line 4—4 of Figure 3.

Fig. 5 is a section on the line 5—5 of Figure 3.

Fig. 6 is a view of the key with the main elements in section.

Fig. 7 is a view with certain upper parts removed to show the bolt locked by the primary elements.

Fig. 8 is a view of the lock with the parts in full, but with portions broken through to show certain mechanism which is secured to the under side of the bottom plate.

Fig. 9 is a section on the line 9—9 of Figure 8.

Fig. 10 is a view with all the parts removed above the line 10—10 of Figure 9.

Fig. 11 is a fragmentary section on the line 11—11 of Figure 7.

Fig. 12 is a fragmentary section on the line 12—12 of Figure 7.

Referring now, to Figures 1, 2 and 3 of the drawings, the device comprises a casing 10, having a top plate 11 which is secured thereto by the screws as shown at 12, 13 etc.

A plate 14 supported by the studs as shown 15, 16 etc. divides a portion of the casing into upper and lower sections. A main

bolt 17 has a relatively thin rear portion 18 which rests upon the plate 14, being guided by the slots 19 and 20. For further

comprehension of this bolt, reference will be had to the fragmentary views 11 and 12 in

which it will be seen that a downward disposed member 21 is provided with slots 22 and 23. This member rests against the upper edge of the plate 14 as seen at 24 in Figure 3.

Referring now to Figure 7, it will be seen that the bolt when locked, is engaged in the notch 25 by the pin 26 which is affixed to the tumbler 27, which tumbler swings on an arc from the pivot 28. The notch 29 holds the bolt back when in its inoperative position, it being then engaged by the said pin 26.

The bolt is thrown by inserting and turning the key 30 which is illustrated in Figure 6 of the drawings. This key is provided with a primary bit 31 which is integral with the sleeve 32. The inner shank 33 being firmly affixed to the ring base 34. A supplemental bit 35 is integral with the shank 33. The primary bit 31 has a recess 36 into which the supplemental bit 35 recedes when the sleeve 32 is forced forward by the spring 37. It is possible for the primary bit and sleeve to fully revolve on the shank when the said sleeve is forced back sufficiently to give it freedom.

The key when inserted is maintained in correct position with respect to the primary tumbler 27 by means of the guide sleeve 40 which may be seen in Figure 4. Further details of the key action will be given in connection with the description of the supplemental lock elements.

Referring now to Figures 7 and 10 of the drawings, a swinging segment 45 turns on the pivot 46 and is further supported by a V bearing indicated by the dotted line 47 and further illustrated in other parts of the drawings under that numeral. This segment has a range of movement within the aperture 48 in the plate 14. A supplemental key hole is located in one side of the said segment at 49 and is brought into line with the guide sleeve 40 when the segment is swung to the left by the action of the lever 51 and the pin 52. This alignment occurs when the bit 31 of the key is turned against the tumbler 27. A tension spring 44, seen in Figure 2, holds the said segment in its normal position.

Mounted on the under side of the plate 14 and guided by the pivot 46 and the pin 52 is the supplemental bolt 53 seen best in Figure 10. This bolt has stop members 54 and 55 and a key aperture 56. Tumblers

as shown at 57 are provided with stop slots as shown at 58, which engage the pin 59, this pin being affixed to the supplementary bolt. Springs as shown at 60 bear against the pin 61 and restrain the said tumblers. When thrown, this supplemental bolt, by means of the stop members 54 and 55 engages the slots 22 and 23 of the main bolt.

When this main bolt 17 is thrown by the turning of the key bit 31 engaging the slot 62 seen in Figure 7, the said bit arrives at a position in which it points diagonally upward to the left as seen in Figure 8 of the drawings. Now, with continued reference to Figure 8 and also to Figure 9 it will be seen that in this position it is in line with the supplemental key hole 49 which has been brought under it by the swinging of the segment 45. It is necessary to hold it in this position in order to pick up the supplemental bit 35 when same is to be withdrawn, and in order to do this, the latch 63 is provided, and is constructed and operated as follows.

The said latch is supported by the shaft 64 which passes through the lock casing and has secured at its extremity a crank 65. This crank is pivotally attached to the draw bar 66 which has a foot piece 67. This foot piece engages the lever 68 which is supported within the bracket 69 by means of the pin 70. A plunger 71 rests on the said lever and passes upward through the casing to a point in alignment with the supplemental key hole when same is in operative position. The latch is limited in movement by the slot 72 and the pin 73 and is held in tension by the spring 74 which is secured to it and to the plate 14 as shown.

It being understood that the bolt 17 is now thrown and the bit 31 in position as described, the supplemental bit 35 passes through the hole in the segment and its base end at once bears against the plunger 71 and pushes same downward, this pulls on the draw bar 66 and swings the latch 63 into position with its slot 75 engaging and holding the primary bit 31. As long as the supplemental bit is in the lower lock the said latch will hold the bit 31 in this position.

The full action of the lock is therefore as follows.

The key is inserted and turned, the primary bit throws the main bolt and is stopped by the latch member 63, the supplemental key hole comes into alignment, the supplemental key passes through and in turning throws the supplemental bolt which engages the slots in the main bolt plate, the supplemental key aligns with the main bit and is withdrawn, and the double locking of the main bolt is accomplished.

While I have shown and described the preferred embodiment of the invention, I

do not wish to be held rigidly to the exact details of construction as illustrated, but claim the right to such minor modifications as may come within the scope of the appended claims.

Having thus described my invention, what I claim as new and desire to secure by Letters Patent, is as follows:

1. In a compound lock, a casing, a main bolt slidably mounted therein, means to secure the said bolt against withdrawal, and also mounted within the said casing, a supplemental bolt in position to engage the bolt first mentioned, a plate separating the said supplemental bolt from the main bolt elements, a movable member with a supplemental key aperture mounted on the plate, means to bring the said supplemental aperture into alignment with a main key hole, and means to actuate the said supplemental bolt and to secure same in operative position.

2. In a compound lock, a casing, a main bolt slidably mounted therein, means to secure the said bolt against withdrawal, and also mounted within the said casing, a supplemental bolt in position to engage the bolt first mentioned, a plate separating the said supplemental bolt from the main bolt elements, a movable member with a supplemental key aperture, and means to bring the said supplemental aperture into alignment with a main key hole, so that a key may fit within the said key hole, the said key having a main bit and a supplemental bit adjacent thereto and adapted to engage the actuating elements of the lock mechanism.

3. In a compound lock, a casing, a main bolt slidably mounted therein, stop members on the main bolt and adapted to engage a suitable tumbler, and a downturned element slotted to receive the stop members of a supplemental bolt, a plate upon which the said main bolt rests and under which the said supplemental bolt is movably mounted, a pivoted segment mounted on said plate and a supplemental key hole therein, suitable stop members adjacent to the said supplemental bolt, the lock being operable by a compound key having primary and supplemental bit members, and means to hold the primary bit of the said key during the rotation of the supplemental member, substantially as shown and described.

4. In a compound lock, a casing, a main bolt slidably mounted therein, means to secure the said bolt against withdrawal, and also mounted within the said casing, a supplemental bolt in position to engage the bolt first mentioned, a plate separating the said supplemental bolt from the main bolt elements a movable member with a supplemental key hole being mounted on the plate, the said movable member being segmental in form and pivoted at its apex and having thereon a pin by a lever engaging the pin,

which lever, acted upon by a main tumbler, serves to swing the said member and to bring the said supplemental key hole in operative alignment, the lock being operable by a compound key having main and auxiliary bit members, substantially as shown and described.

5. In a compound lock, a casing, a main bolt slidably mounted therein, means to secure the said bolt against withdrawal, and also mounted within the said casing, a supplemental bolt in position to engage the bolt first mentioned, a plate separating the said supplemental bolt from the main bolt elements a movable member on the plate and having a supplemental key aperture, means

to bring the said supplemental aperture into alignment with a main key hole, a plunger pin located below the said key hole and in alignment therewith, a rocker lever engaging the plunger pin, a draw member engaged by the rocker lever to turn the shaft of a latch element, which element is slotted to engage a main key bit when in operative position, the lock being operable by a key having a main bit and a supplemental bit adjacent thereto, substantially as shown and described.

In testimony whereof I have affixed my signature.

FRANK BORSODY.
